(57) **CLAIM**

The ornamental design for a multi-purpose bag as shown and described.

DESCRIPTION

FIG. 1 is a front view of a multi-purpose bag showing my new design in the closed configuration;

FIG. 2 is a left-side view thereof in the closed configuration; FIG. 3 is a right-side view thereof in the closed configuration;

FIG. 4 is a rear view thereof in the closed configuration;

FIG. 5 is a top view thereof in the closed configuration;

FIG. 6 is a bottom view thereof in the closed configuration;

FIG. 7 is a top front perspective view thereof in the closed configuration;

FIG. 8 is a bottom rear perspective view thereof in the closed configuration;

FIG. 9 is a perspective view, showing the multi-purpose bag of FIG. 1 in an alternate, opened configuration showing the inside of the multi-purpose bag; and,

FIG. 10 is an alternate perspective view, showing the multi-purpose bag of FIG. 1 in an alternate, opened configuration, showing the outside of the multi-purpose bag.

The broken line showing of pull tabs, a button, a clip, and a roll of bags is included for the purpose of illustrating environmental structure and forms no part of the claimed design.

1 Claim, 10 Drawing Sheets
